3

are noted in the kidney tissues, a comparison being slightly in favor of compound A.

Clinical investigations have also been made. Thus, 10 patients with edema were given compound A orally with the following results:

In 4 patients a questionable increase of diuresis was noted, in 2 patients a moderate increase occurred, and 4 patients had a pronounced increase. The average increase in the diuresis for all 10 patients was 65 percent.

In another investigation 4 patients with heart insufficiency and edemas were given compound A in daily doses of 20, 20, 30 and 10 mg. Hg, respectively, with the results of increased diuresis and weight losses of 2.2 kg. (in 4 days), 4.5 kg. (in 11 days), 5.5 kg. (in 5 days) and 1 kg. (in 5 days), respectively.

A third investigation was carried out as follows. 16 patients were given compound A in daily doses corresponding to 40 mg. Hg. The average increase in diuresis was 81 percent, whereby 6 patients showed less than 35 percent increase, 4 patients showed 35 to 100 percent increase, and 6 patients showed more than 100 percent increase.

The average weight loss for 12 patients in the observation period was 1.8 kg.

Two of the patients had slight nausea, and two had severe nausea, vomiting and diarrhea, but no really serious secondary effects were noticed.

In a fourth investigation, the daily doses of compound A were corresponding to 60 mg. Hg. 14 patients were involved, and the average increase in diuresis was 131 percent.

2 patients showed less than 35 percent increase, 5 patients showed 35 to 100 percent increase, and 7 patients showed more than 100 percent increase.

Secondary effects were noted in 3 patients getting nausea, vomiting and diarrhea.

The average weight loss for all 14 patients during the observation period was 2.9 kg.

As will be seen from the preceding description the compounds of the invention are preferably administered orally.

A convenient dosage unit corresponds to 10 mg. Hg, and a daily dose for adults preferably corresponds to from 0.1 to 1 mg. Hg per kg. body weight.

A preferred dosage unit form is a tablet containing a compound of the invention in a proportion corresponding to a content of 10 mg. of mercury, and the preferred compound is the theophylline compound.

The following non-limitative examples illustrate the preparation of the compounds of the invention.

EXAMPLE 1

14 g. of allyl succinimide and 32 g. of mercuric acetate in 120 ccs. of methanol were refluxed for 8 hours, whereafter the reaction mixture was evaporated in vacuum to a syrupy consistency. The residue was dissolved in 150

4

ccs. of methanol, 20 g. of theophylline were added, and the mixture was refluxed for 3 hours, filtered and then cooled to -10° C. After standing for 24 hours, the precipitate was filtered off and re-crystallized from methanol, yielding 24 g. of 3-mercuric-2-methoxy-1-succinimidopropane, theophylline with M. P. 115° C.

By re-crystallization from acetone, modifications can be obtained melting at 146° C. and 192° C., respectively, due to loss of water from the complex.

EXAMPLE 2

14 g. of allyl succinimide and 32 g. of mercuric acetate in 120 ccs. of methanol were refluxed for 8 hours. The reaction mixture, containing 3-acetoxy-mercuric-2-methoxy-1-succinimidopropane, was evaporated in vacuum to a syrup, which was stirred for $\frac{1}{2}$ hour with a surplus of a saturated aqueous solution of sodium chloride. The thereby precipitated 3-chloromercuric-2-methoxy-1-succinimidopropane was sucked off and re-crystallized from methanol as a white microcrystalline power with M. P. 145° C. The yield as calculated from allyl succinimide was 80 percent.

We claim:

1. 3-mercuric-2-methoxy-1-succinimidopropane derivatives selected from the group consisting of compounds of the formulae:

wherein X denotes an acid residue selected from the group consisting of chlorine and acetoxy, and

wherein HY denotes a purine compound selected from the group consisting of theophylline, caffeine, and theobromine.

2. Theophylline - 3-hydroxymercuric-2-methoxy-1-succinimidopropane.

3. 3 - acetoxymercuric - 2 - methoxy - 1 - succinimidopropane.

4. 3-chloromercuric-2-methoxy-1-succinimidopropane.

5. In a process for the production of 3-mercuric-2-methoxy-1-succinimidopropane derivatives, the step of refluxing allyl succinimide with mercuric acetate in methanolic solution to form a reaction mixture and heating the reaction mixture with theophylline.
